J. D. PEDERSEN,

FIREARM.

APPLICATION FILED APR. 2, 1920.

1,423,358.

Patented July 18, 1922.

4th Inventor:
John D. Pedersen,

48' By his Atty, J. F. Richards.

UNITED STATES PATENT OFFICE.

JOHN D. PEDERSEN, OF JACKSON, WYOMING.

FIREARM.

1,423,358.

Specification of Letters Patent. Patented July 18, 1922.

Original application filed July 17, 1919, Serial No. 311,689. Divided and this application filed April 2, 1920. Serial No. 370,830.

To all whom it may concern:

Be it known that I, JOHN D. PEDERSEN, a citizen of the United States, residing in Jackson, in the county of Lincoln and State 5 of Wyoming, have invented certain new and useful Improvements in Firearms, of which the following is a specification.

This invention relates more especially to that class of firearms which is usually designated as small arms, and a principal object 10 of the invention is to provide an improved barrel mounting construction which is particularly applicable to auto-loading and automatic pistols.

15 An improved auto-loading pistol of this kind is described in my Patent No. 1,348,733, dated August 3, 1920, and granted on my co-pending application, Serial No. 311,689, filed July 17, 1919, this being a renewal of 20 application Serial No. 42,774, filed July 30, 1915. Therefore, for convenience of illustration, I have shown my present improvements as arranged and applied to the particular kind of auto-loading pistol which is 25 shown in the drawings of said patent, to which reference may be had.

A feature of my barrel mounting construction is that the barrel of the firearm is carried within the main slide of the firearm 30 and carried by the main slide, and is thus held in alignment with the slideway surfaces of the main slide without having any support on or directly by the frame of the firearm in a direction transversely of the bore 35 of the barrel.

In the accompanying drawings, which illustrate an embodiment of my invention, Figure 1, is a side view, partly broken away to show details, of a pistol provided with 40 my barrel mounting construction.

Figure 2 is a front end elevation of a pistol provided with my barrel mounting construction.

Figure 2^a, is a plan view of the forward 45 portion of the frame or receiver of the pistol.

Fig. 3, is a fragmentary longitudinal vertical sectional view, on an enlarged scale, of a pistol provided with my barrel mounting construction for illustrating the construction and arrangement of the operative parts of my barrel mounting.

Fig. 4, is the same as Fig. 3, except that

the main slide of the pistol is partly retracted, and the sleeve of the barrel mounting is 55 drawn forward for unlocking the barrel of the pistol which then may be revolved and drawn out.

Fig. 5, is a sectional view on the line 5—5 of Fig. 3, as seen from the left hand of 60 said line looking in the direction of the arrow, the main slide being retracted as shown in Fig. 4.

Fig. 5^a, is an end view of the barrel of the pistol as seen from the left hand in Fig. 65 3^a, and from the right hand in Figs. 3 and 4.

Fig. 6, is a horizontal and fragmentary sectional view for more fully showing certain details of a means (which comprises a barrel-guiding ring that slides within the 70 main slide) for detaining the barrel in proper rotative position while free of any supportive connection with the frame of the pistol.

Figure 7, is a perspective view of the 75 barrel-guiding ring, together with certain co-acting details, as seen in an oblique direction from a point to the right hand of Fig. 6.

Similar characters designate like parts in 80 all the views.

The main slide, C, is shown so formed and arranged that the barrel D may be carried within and thereby, and may thus be held in alignment with the slideway surfaces of this slide without having any support on 85 or directly by, the frame itself in a direction transversely of the bore of the barrel. Thus the main slide in the described preferred form thereof, constitutes a barrel-carrier,—and also a barrel-carrying power-slide,—the barrel being fitted, equipped and arranged for a reciprocatory or sliding movement within and relatively to said carrier during the sliding movement of the carrier (through an equal stroke) on and 90 relatively to the frame. For effecting such sliding movement of the barrel within the barrel-carrier, some suitable barrel-positioning means or device should be provided and arranged as between the barrel and the 100 frame for preventing any considerable longitudinal movement of the barrel relatively to the frame during the said sliding movement of the barrel-carrier upon and relatively to the frame. By the term barrel-positioning, as applied to means, connecting 105

or device, I refer, of course, to the holding or detaining of the barrel against movement in a direction longitudinally of the frame.

The frame B is shown provided with a 5 guideway for the power-slide C, which power-slide in practice will be provided with the usual firearm-sights, as t^6 , t^6 . In Figs. 1, 3, and 4, these sights are indicated as being of a well-known and simple kind, 10 but other kinds of sights may be used in place thereof. Said guideway may be said to comprise, in the preferred form thereof, two slideways, or guides as 3^e , 3^e , located one on either side of the frame, (see Fig. 5). 15 The power-slide C is mounted on the frame in sliding engagement with said slideways, and has formed therein a barrel-chamber, 3^j , Figs. 3 and 4. The barrel D, is located and arranged in said barrel-chamber for sliding 20 and rotative movements within said chamber and relatively to the power-slide, and free of any supportive engagement with the frame.

The breech action-slide C is shown with 25 the barrel-chamber 3^j sufficiently enlarged for the barrel D, with the slide-spring 4^d and guide-ring 4^e thereon, (Figs 3 and 4) to be inserted from the forward end thereof. The forward end, 4^p , of the barrel is held in 30 alinement and guided by a bushing or bearing 3^f which is removably fixed in the forward end, 3^k , of the member C, (see Figs. 3 and 4). Said bearing ring 3^f also forms the bearing or abutment against which the slide- 35 spring 4^d acts at all times for moving or holding the main-slide forwardly on the frame B. The ring 3^f is, or may be, held in place by a screw thread, in the well-known manner indicated in Fig. 3 by the lines of 40 the drawing.

On the barrel is mounted a bushing 4^e of suitable internal diameter to pass over the front end 4^p of the barrel and to bear against a shoulder, 4^k , formed by the slightly enlarged rear end 4^e of the barrel D. This 45 bushing 4^e has an annular recess 4^m at its front end to receive the rear end 4^n of said slide spring 4^d , the external diameter of the bushing being made to produce a close but 50 freely working fit in the corresponding bore 3^j in the forward end 3^k of the slide. (see Figs. 3 and 4).

The chamber 3^j in the forward end 3^k of the slide C which receives and guides the 55 barrel-bushing, is reduced in diameter at a point just to the rear of the rear end of the bushing 4^e , when the parts are assembled in the arm and the slide C is in its forward or "breeched-up" position, Fig. 3. The 60 diameter of this reduced bore is slightly larger than the diameter of the enlarged rear end 4^e of the barrel D, so that the slide may move longitudinally over the barrel D.

For holding the barrel D, in proper position within the slide C, during the sliding

movements of said member C relatively to the frame B, the barrel may have formed and transversely-located therein a single recess, as 4^v , (Fig. 3^a) and the frame may have a correspondingly formed and located projection, as 2^e , extending into said recess, (Figs. 3 and 4), and may have forward and rearward surfaces 2^w , 2^x , (Fig. 6) engaging with the forward and rearward surfaces 4^u and 4^v , respectively, of the recess,—see Fig. 75 3^a. A clear space is shown at s^1 and also at s^2 , s^2 , Figs. 3 and 4, so as to prevent the barrel from having any supportive bearing on, or supported engagement with, the frame, and thereby prevent, also, the positioning engagement of the barrel and frame from having a disturbing effect upon the alinement relations of and as between the barrel and its carrying-slide C and the sights thereon. Should it be deemed desirable, in 80 any given instance, to provide a larger surface area of the contacting faces at the recess 4^v , those faces may be increased in size or in number, or both; also, if preferred, other suitable or well-known means or device (not 85 shown in this application) may be substituted, within the purview of my present invention, for said barrel-recess and frame-projection.

The above described pairs of barrel-locating surfaces, are preferably of a screw-like, or helical form and arrangement, (Figs. 2^a and 6), so that in assembling the mechanism the barrel by partial rotation thereof may be thus drawn backwardly during the 90 operation of engaging the barrel-end 4^e with the frame B. Just to the rear of the said surface 2^w , the receiver B has a segmental annular drawing shoulder 2^e , Figs. 4 and 5, so arranged that when the barrel D is 95 partially revolved to its position of normal engagement with the receiver B, the rear end of the barrel D is drawn back in a positive manner against the shoulder 2^e . Since the forward movement of the breech block 100 E is limited by striking the rear end 4^e of the barrel D, (Fig. 3), this arrangement of the said locating and drawing surfaces locates the rear end of the barrel longitudinally in the frame with extreme accuracy. 110

The barrel D is shown provided with rifling, as 4^b , (see Fig. 3) which is of the same "hand" as the screw-like locating-surfaces at the rear end of the barrel. One effect of this is that when the projectile is advancing through the barrel D, its inertia resists the "spin" given to the projectile by the rifling, so that this inertia or resistance of the projectile tends to rotate the barrel D in a direction opposite to the twist of the rifling. This rotative impulse imparted to the barrel in the said opposite direction from the twist of the rifling, has the effect of tending to move the barrel D backward with respect to the receiver B and thus,—controlled by 120 125 130

the screw-like engaging surfaces of the barrel and the receiver,—to securely draw the barrel backward into engagement with the aforesaid segmental annular drawing shoulder 2^e located in the receiver.

It will be understood that prior to the firing of the shot, and if there is a relatively free fit between the barrel D and the slide C, the barrel may not at that time have been 10 rotated precisely to its true position and therefore may not be in actual or firm contact with said annular locating or drawing shoulder, 2^e, in the receiver B, but as the projectile advances up the bore 4^f, this contact will normally be effected.

The slide C is provided on each side with a longitudinal groove 3^e, and with a pair of parallel ribs (Fig. 5) at the bottom side of the slide. The top of the receiver B, (which 20 should or generally may be a flat surface), carries on its sides a corresponding pair of grooves 2^d, so that the slide C may be assembled on the receiver from the front; the said ribs at the bottom of the slide C taking 25 into the said grooves near the top of the receiver. The said ribs formed at the bottom of the slide open rearwardly, and the slot in the bottom of the slide C is terminated at its front end by a stop abutment 3^p. A corresponding abutment, 2ⁱ, to engage this stop abutment 3^p on the slide, is located near the front of the receiver B, so that the rearward movement of the slide C will be positively limited when the slide is moved backward 35 to engage these two surfaces 3^p and 2ⁱ, as in Figs. 3 and 4. It follows from this that the operator of the arm could not be injured by the slide being thrown to the rear end off of the receiver.

40 To assemble the slide C to the receiver B, the rear ends of the ribs on the slide are engaged into the corresponding grooves at the front of the receiver and the slide carrying the breechblock E, and the barrel D, 45 assembled as above described, is slid backward on to the receiver until the rear end of the barrel D brings up against the aforesaid segmental annular shoulder, 2^e, of the receiver. While the slide C is held in this 50 position (not shown) the barrel D is rotated into its normal engagement with the rib 2^e of the receiver B. The slide C is then released and under the action of the said slide-spring is drawn forward to its normal or breeched-up position, as in Figs. 1 and 3.

55 In order to remove the slide C and barrel D from the receiver B, the slide is moved backward on the receiver to a position (about midway between positions Figs. 3 and 4) where the shouldered end at 3^z, formed by the rear end of the large bore, 3^j, in the slide will be to the rearward of the rear end of the barrel. The barrel is now 60 grasped at the muzzle and rotated one-half 65 turn in the proper direction to disengage its

faces 4^a, 4^v, from the receiver B, then the slide and barrel are pulled forward off of the receiver.

In connection with the arrangements already described in connection with Figs. 4, 5 and 6, for slidably supporting the barrel within the main slide C, some convenient means or device may be provided for normally preventing the barrel from being rotated in a direction for releasing or retracting the rearward end, 4^e, of the barrel from its normal position relative to the frame. In practice, such a supplemental device, in view of the manner in which the barrel engages the frame, will not always be essential. 75 One convenient arrangement, however, for releasably detaining the barrel against a retractive rotation is particularly illustrated in and by Figs. 3, 4, 5 and 6. Said retaining device in the form here illustrated comprises a rearwardly extending blade or projection 4^h which is preferably integral with the guide-bushing or sleeve 4^e. Referring to Figs. 5 and 6, this projecting part 4^h is shown located below the barrel and within 80 a groove or channel therefor which is formed in the barrel; and, the rearward end 4^g, of said blade or projection is shown beveled so as to bear against an inclined face 2ⁱ formed in the rib 2^e of the frame B. The 85 pressure of the spring 4^d by forcing the sleeve 4^e in a rearward direction (toward the right hand in Fig. 6) operates in connection with said inclined face 2ⁱ for turning the sleeve 4^e and the barrel together in 90 the proper direction by a pressure of the projection 4^h against the face 4ⁱ of the barrel, as will be obvious from a comparison of Figs. 3, 4, 5 and 6. By these arrangements, 95 the mounting and the precision of alinement 100 of the barrel relatively to the power-slide, and relatively to firearm-sights thereon, is made independent of, and unaffected by, the alinement relations between the power-slide and the frame, and also independent of the 105 positioning connection between the barrel and the frame.

Having thus described my invention, I claim:

1. In a firearm, in combination, a frame 115 of the firearm provided with a shoulder, a main slide supported by said frame and movable thereon and provided with a barrel-chamber, a barrel in said barrel-chamber rotatable for engaging the rear end of the 120 barrel with said shoulder of the frame, means for supporting the barrel in said barrel-chamber independently of said frame of the firearm, and means on the barrel coacting with means on the frame of the firearm 125 for drawing the barrel rearwardly to bring the rear end of the barrel into engagement with said shoulder of the frame by partial rotation of the barrel.

2. In a firearm, in combination, a frame 130

of the firearm provided with a shoulder, a main slide supported by said frame and movable thereon and provided with a barrel-chamber, a barrel in said barrel-chamber 5 rotatable for engaging the rear end of the barrel with said shoulder of the frame, means engaging the main slide and barrel for supporting the barrel in said barrel-chamber forwardly, means engaging the main slide and barrel for supporting the barrel in said barrel-chamber rearwardly independently of the frame of the firearm, and means for drawing the barrel rearwardly to bring the rear end of the barrel into engagement with said shoulder by partial rotation of the barrel.

3. In a firearm, in combination, a frame of the firearm provided with a shoulder, a main slide supported by said frame and provided with a barrel-chamber, a barrel in said barrel-chamber rotatable for engaging the rear end of the barrel with said shoulder of the frame, means for supporting the barrel in said barrel-chamber forwardly, means 15 for supporting the barrel in said barrel-chamber rearwardly independently of the frame of the firearm, and means on the barrel coacting with means on the frame of the firearm for drawing the barrel rearwardly 30 to bring the rear end of the barrel into engagement with said shoulder by partial rotation of the barrel.

4. In a firearm, in combination, a frame of the firearm provided with a shoulder, a main slide supported by said frame and movable thereon and provided with a barrel-chamber, a barrel in said barrel-chamber rotatable for engaging the rear end of the barrel with said shoulder of the frame, means 10 engaging the main slide and barrel for supporting the barrel in said barrel-chamber forwardly, means engaging the main slide and barrel for supporting the barrel in said barrel-chamber rearwardly independently 15 of the frame of the firearm, and helical means on the barrel coacting with helical means on the frame of the firearm for drawing the barrel rearwardly, to bring the rear end of the barrel into engagement with said 20 shoulder of the frame by partial rotation of the barrel, said helical means being non-supportive of the barrel.

5. In a firearm, in combination, a frame of the firearm provided with a shoulder, a main slide supported by said frame and movable thereon, a barrel carried by the main slide and held in alinement therewith without support for the barrel on said frame 25 in a direction transversely of the bore of the barrel, the barrel being rotatable for engaging the rear end thereof with said shoulder of the frame, and means on the barrel coacting with means on the frame of the firearm for drawing the barrel rearwardly to bring the rear end of the barrel 30

into engagement with said shoulder of the frame by partial rotation of the barrel.

6. In a firearm, in combination, a frame of the firearm provided with a shoulder, a main slide supported by said frame and movable thereon, a barrel carried by the main slide and held in alinement therewith without support for the barrel on said frame in a direction transversely of the bore of the barrel, the barrel being rotatable for 50 engaging the rear end thereof with said shoulder of the frame, and helical means on the barrel coactive with helical means on the frame of the firearm for drawing the barrel rearwardly to bring the rear end of the barrel into engagement with said shoulder of the frame by partial rotation of the barrel.

7. In a firearm, in combination, a frame of the firearm provided with a shoulder, a main slide supported by said frame and movable thereon, a barrel carried by the main slide and held in alinement therewith without support for the barrel on said frame in a direction transversely of the bore of the barrel, means for preventing longitudinal movement of the barrel relatively to the frame during movement of the slide upon said frame, the barrel being rotatable for engaging the rear end thereof with said shoulder of the frame, and helical means on the barrel coacting with helical means on the frame of the firearm for drawing the barrel rearwardly to bring the rear end of the barrel into engagement with said shoulder of the frame by partial rotation of the barrel.

8. In a firearm, in combination, a frame of the firearm provided with a shoulder, a main slide supported by said frame and movable thereon and provided with a barrel-chamber, a barrel in said barrel-chamber rotatable for engaging the rear end of the barrel with said shoulder of the frame, means for supporting the barrel in said barrel-chamber forwardly, means for supporting the barrel in said barrel-chamber rearwardly, means for drawing the barrel rearwardly to bring the rear end of the barrel into engagement with said shoulder of the frame when the barrel is rotated, and means for preventing rotation of the barrel in a direction for releasing the rear end of the barrel from engagement with said shoulder of the frame.

9. In a firearm, in combination, a frame of the firearm provided with a shoulder, a main slide supported by said frame and movable thereon and provided with a barrel-chamber, a barrel in said chamber rotatable for engaging the rear end of the barrel with said shoulder of the frame, means engaging the main slide and engaging the barrel for supporting the barrel in said barrel-chamber forwardly, means engaging the main slide and engaging the barrel for 120

125

130

- supporting the barrel in said barrel-chamber rearwardly, means for drawing the barrel rearwardly to bring the rear end of the barrel into engagement with said shoulder of the frame when the barrel is rotated, and means for preventing rotation of the barrel in a direction for releasing the rear end of the barrel from engagement with said shoulder of the frame.

5 10. In a firearm, in combination, a frame of the firearm provided with a shoulder, a main slide supported by said frame and movable thereon and provided with a barrel-chamber, a barrel in said chamber rotatable for engaging the rear end of the barrel with said shoulder of the frame, means engaging the main slide and engaging the barrel for supporting the barrel in said barrel-chamber forwardly, means engaging 15 the main slide and engaging the barrel for supporting the barrel in said barrel-chamber rearwardly, helical means for drawing the barrel rearwardly to bring the rear end of the barrel into engagement with said shoulder of the frame when the barrel is rotated, and means coacting with the barrel and with the frame of the firearm for preventing rotation of the barrel in a direction for releasing the rear end of the barrel from engagement with said shoulder of the frame.

20 25 30 35 40 45 50 55 60 65 70 75 80 85 90 95 100 105 110 115 120 125 130 135

11. In a firearm, in combination, a frame of the firearm provided with a shoulder, a main slide supported by said frame and movable thereon and provided with a barrel-chamber, a barrel in said chamber rotatable for engagement of the rear end of the barrel with said shoulder of the frame, means engaging the main slide and engaging the barrel for supporting the barrel in said barrel-chamber forwardly, means engaging the main slide and engaging the barrel for supporting the barrel in said barrel-chamber rearwardly, helical means on the barrel coacting with helical means on the frame of the firearm for drawing the barrel rearwardly to bring the rear end of the barrel into engagement with said shoulder of the frame when the barrel is rotated, and projection means coacting with the barrel and with the frame of the firearm for preventing rotation of the barrel in a direction for releasing the rear end of the barrel from engagement with said shoulder of the frame, said projection means for preventing rotation being comprised in said means for supporting the barrel in the barrel-chamber rearwardly.

14. In a firearm, in combination, a frame of the firearm provided with slide-ways and a shoulder, a main slide supported by said frame and reciprocatable on said slide-ways, a barrel carried within and by the main slide and rotatable for engaging the rear end of the barrel with said shoulder of the frame, the main slide being movable over the barrel when reciprocated, a slide spring, means for retaining the barrel within the main slide during sliding movements of the main slide relative to the frame of the firearm, means for drawing the barrel rearwardly to bring the rear end thereof into engagement with said shoulder of the frame of the fire arms, said means consisting of transversely located means on the barrel non-supportive of the barrel by the frame of the fire-arm and coacting with transversely located means on said frame, and means coacting with the barrel and with the frame of the firearm for preventing rotation of the barrel 130

in a direction for releasing the rear end of the barrel from engagement with said shoulder of the frame.

15. In a firearm, in combination, a frame of the firearm provided with slideways and a shoulder, a main slide supported by said frame and reciprocatable on said slideways and provided with a barrel-chamber, a barrel in said barrel-chamber rotatable to bring the 10 rear end of the barrel into engagement with said shoulder and provided with a channel, the main slide being movable over said barrel when reciprocated, a bearing ring engaging the main slide and engaging the 15 barrel for supporting the barrel in said barrel-chamber forwardly, a guide-ring engaging the main slide and engaging the barrel for supporting the barrel in said barrel-chamber rearwardly, the guide-sleeve 20 being provided with an extending blade having a beveled edge, a spring around the barrel and abutting said bearing ring and said guide-sleeve, means consisting of a transversely-located recess in the barrel 25 acting with a correspondingly located projection of the frame of the firearm non-supportive of the barrel by the frame of the firearm for retaining the barrel in position in said barrel-chamber, and for drawing the 30 barrel rearwardly to bring the rear end of the barrel into engagement with said shoulder of the frame when the barrel is rotated, and an inclined face on the frame of the firearm, said blade of the guide sleeve 35 engaging said channel of the barrel and the beveled edge of the blade engaging said inclined face for preventing rotation of the barrel in a direction for releasing the rear end of the barrel from engagement with said 40 shoulder of the frame.

16. In a firearm, in combination, a frame of the firearm provided with slideways and having a rib with an inclined face formed

therein, a main slide provided with slideway surfaces for engaging the slideways of 45 said frame, a slide-spring, a barrel provided with a channel formed therein and rotatable to bring the rear end of the barrel into engagement with said rib, said barrel being carried by the main slide without support 50 for the barrel on the frame of the firearm in a direction transversely to the bore of the barrel, and means for preventing the barrel from being rotated in a direction for releasing the rearward end of the barrel 55 from its normal position relative to the frame; said means comprising a guide-sleeve engaging the main slide and engaging said slide spring and provided with a blade engaging said inclined face of the frame. 60

17. In a firearm, in combination, a frame of the firearm provided with slideways and having a rib with an inclined face formed 65 therein, a main slide provided with slideway surfaces for engaging the slideways of said frame, a slide-spring, a barrel provided with a channel formed therein, said barrel being carried by the main slide and held in alignment with the slideway surfaces of the main slide without support for the barrel on the frame of the firearm in a direction 70 transversely of the bore of the barrel, and means for preventing the barrel from being rotated in a direction for releasing the rearward end of the barrel from its normal position relative to the frame; said means comprising a guide-sleeve engaging the main slide and engaging said slide-spring and provided with a blade engaging said channel having a beveled rearward end engaging 75 said inclined face of the frame. 80
